UNITED STATES PATENT OFFICE.

FRANCIS T. ROBINSON, OF BROOKLYN, NEW YORK, ASSIGNOR TO ARKELL SAFETY BAG COMPANY, OF NEW YORK, N. Y., A CORPORATION OF NEW YORK.

BAG-BOTTOM-FORMING MACHINE.

Application filed May 26, 1923. Serial No. 641,535.

To all whom it may concern:

Be it known that FRANCIS T. ROBINSON, a citizen of the United States, residing in the borough of Brooklyn, county of Kings, 5 and State of New York, has invented new and useful Improvements in Bag-Bottom-Forming Machines, of which the following is a specification.

The present invention relates to bag bottom forming machines and more particularly to a machine on which flat bags, without a formed bottom, may be converted into bags having a formed flat bottom suitable for use as linings for barrels, boxes or the 15 like.

Paper bags are commonly made flat by folding a rectangular paper blank upon itself and pasting or stitching the opposite edges of the blank at the bottom and at one 20 side. These flat bags do not have a formed bottom, i. e. one which will open out flat, and, hence, have not been considered suitable linings for boxes, barrels or the like. Paper bags known as "square bottom bags" 25 (whose bottoms are merely rectangular) are also made with flat or formed bottoms by cutting, folding and pasting the paper in a predetermined more complicated manner. In these bags the bottom is self-supporting 30 and when the bag is filled with loose material the bottom is substantially flat and is so held on account of the construction of the bag. These square bottom bags are always more expansive to manufacture than 35 the flat bags first referred to, and particularly so when made in large sizes. A formed-bottom bag of the proper size may be used as a box lining and heretofore such linings have been made. The paper was cut, folded 40 and pasted, the operation being carried on to quite an extent by hand on account of the size of automatic machinery that would be needed. Another reason why the large box lining is costly is the enormous variation 45 of dimension in boxes of substantially the same contents.

While a "square" bottom bag can be made to fit practically any flat bottom rectangular box, it is unsuited for use as a lining 50 for barrels or the like. Where it is desired to line these round containers, a specially designed lining has been used. For example, linings for kegs and barrels have been made by taking a tube and sewing in 55 a round bottom. Such a lining is shown

in Blanchard Patent No. 698,790, dated April 29, 1902. These linings are made by crinkling paper in the web, severing the paper into sheets, and sewing or pasting the sides to form a tube. The bottom is 60 completed by sewing in a round piece of crinkled paper. A considerable amount of skilled labor is necessary, especially for cutting the round bottom and for operating the sewing machine for sewing in the round 65 bottom; considerable paper is wasted in making the round bottom.

Flat bags may be formed in several ways. A rectangular blank may be folded upon itself and the bag completed by fastening 70 together the two parallel open edges, or the edges at one end and the side opposite the fold may be fastened together, or the bag may be made by folding the margins of a blank down upon the central portion, the 75 edges of the margin meeting, and then fastening the marginal edges together and the end formed by one of the doubled edges of the blank, or the bag may be formed as on Arkell Patent No. 642,061 dated January 80 30, 1900.

Flat bags of the types above referred to are the most inexpensive bags made. But they are not suitable for linings, because they will not fit into a barrel or box 85 and extend clear to the corners and inside edges. Unless the linings fit the boxes or barrels pressure may soon rupture them.

In the drawings accompanying the present application the only type of bag shown is 90 the one in which the blank is folded to form a collapsed tube and then the end of this tube is closed along a straight line, but it is to be understood that any of the types of bag above described, or any other type 95 of flat bag without a formed bottom may be used as a blank for conversion into a bag or lining with a formed flat bottom.

The properties imparted to paper by crinkling it makes it of great value as a 100 packing material; but to preserve these valuable properties it is necessary to handle the paper in a radically different manner from that which is common for smooth paper; the crinkles must be preserved. Hence, 105 special methods have been developed for manipulating this paper, and the articles made from it. Ordinary bag making machines, for making grocer's bags, would be wholly unsuited for making a crinkled pa- 110

per bag. The present invention has been developed particularly by reason of the peculiarities of crinkled paper.

The principal object of the present invention is to provide a machine on which bags or linings with formed flat bottoms may be expeditiously made out of flat bags without a formed bottom and preferably one on which the formed flat bottom bags 10 may be collapsed for shipment.

The accompanying drawings show for the purposes of illustration two of the many embodiments in which the present invention may take form, one illustrating a machine 15 arranged for making round bottom bags and the other a machine for making square bottom bags.

In these drawings:

Fig. 1 is an elevation of a machine for 20 forming round bottoms showing the parts in one position;

Fig. 2 is an elevation taken in the direction of the arrow 2 of Fig. 1, showing the parts in collapsed position;

25 Fig. 3 is a top plan view of a folding table in the position of Fig. 1;

Figs. 4 and 5 are side and end views 30 illustrating the upper end of one form of machine for making square bottom bags, the spreaders being collapsed;

Fig. 6 is a view taken in the direction of the arrow 6 of Fig. 4;

Fig. 7 is a top plan view of the machine 35 of Figs. 4 and 5 with the folding table extended;

Fig. 8 illustrates one form of flat bag without a formed bottom;

Fig. 9 illustrates the bottom of a bag having 40 a round formed bottom as made on the present machine; and

Fig. 10 illustrates a collapsed square bottom bag as made on the machine of the present invention.

A standard 11, which may be in the form 45 of a heavy piece of square metal stock, is suitably mounted on the base 12, which may conveniently be a comparatively heavy piece of rolled steel. The upper end 12' of the standard is turned down as indicated, and 50 a horizontal cross member 13 is fastened in place by a lock screw 13'. Hinges 14, fastened to the cross member, carry spreaders 15 shown in Fig. 3 in the form of semi-circular pieces of metal. The ends of the 55 cross member are provided with depending guides 13'', for a purpose to be described.

A treadle or foot lever 16 is fastened on an angle iron 17 mounted on the base 12 and the opposite end 18 of the foot lever is connected by a link 19 to a lug 20 mounted on 60 a rod 21. A lock nut 22 is provided for adjusting the position of the lug 20 along the rod. This rod is guided for vertical reciprocation alongside the supporting standard 11 by means of apertured lugs 23 and 24. Near

the upper end of this rod another lug 25 is clamped by means of a lock nut 26 and links 27 and 28 connect the lugs 25 with depending lugs 29 and 30 carried underneath the spreaders 15.

A latch member 31 is pivoted, as shown at 32, to the standard 11. This latching member is connected by a rod 33 to a treadle 34 pivoted at 35 to the bottom of the standard. A spring 36 tends to lift the treadle 75 34 and to push the latching member 31 over against a fixed stop 37, carried on the standard. The lug 20 is provided with a projection 38 which may conveniently be an extension of the bolt used for fastening the 80 link 19 to the lug. This projection is so disposed that, upon depressing the treadle 16 to raise the rod 21, it passes by the rear curved edge 39 of the latching member 31 whereupon the spring 36 forces the upper edge 40 of the latch underneath the projection 38. In this way the folding table made up of the spreaders 15-15 is moved from the position of Fig. 1 to the position 90 of Fig. 2. To restore the machine to the position of Fig. 1, it is only necessary for the operator to depress the lever 34, which releases the latching member and permits the mechanism to drop either under the influence of gravity or of a spring 41, to the 95 position of Fig. 1.

In operating the machine, parts are first moved to the position shown in Fig. 2, whereupon a flat bag B having a bottom seam 42 and a side seam 43 (as shown in Fig. 8) is opened up slightly and passed down over the collapsed spreaders, being guided by the members 13''. The position of such a bag is illustrated in dotted lines in Fig. 2. The operator then releases the latching mechanism and permits the machine to assume the position shown in Figs. 1 and 3, the lugs 25 and 23 forming a stop. As shown in this position, the bag is spread out over the folding table, the corners 44 and 45 of the bag projecting above the folding table as indicated in dotted lines in Fig. 1. The operator then passes the hands about the edge of the spreaders and then toward one another to fold the corners inwardly as indicated in Fig. 9. This provides a formed bottom having a configuration of the top of the folding table. The operator then steps on the treadle 16 returning the parts to the position shown in Fig. 2. The bag with the formed bottom is collapsed by bringing the parts 46 and 47 toward one another and the bag is withdrawn from the machine in a collapsed condition ready for shipment. The guides 13'' direct the movement of the bag and prevent injury of the bags by the ends of the cross member.

The supporting standard 11 and operating parts for the folding table may be made to fit any folding table, and the ma- 130

chine changed to operate on different sized bags by merely removing the lock screw 13', and the bolts fastening the links 27 and 28 to the lugs 29 and 30, and substituting the 5 different sized parts.

The machine illustrated in Figs. 4 to 7 inclusive has been designed for making square bottom bags with infolded side tucks. The lower end of the machine may be the 10 same as the lower end of the machine of Figs. 1 and 2 and, therefore, the drawings illustrate only the upper end of the machine.

A supporting standard 50 carries at its 15 upper end a horizontal cross member 51, similar to the cross member 13 of Fig. 2. Spreaders 52—52 are mounted on the cross member 51 by means of hinges 53. In the form shown in the drawings, these are ordinary butt hinges with one strap 54 fastened to the cross member 51 by bolts 55 and with the other strap fastened to the spreaders 52 by rivets 56. Of course any other suitable arrangement could be employed. 20 The spreaders 52 are provided with depending lugs 57 to which links 58 and 59 are connected. These links extend downwardly in the same fashion as the links 27 and 28 of Fig. 1 and may be connected with similar 25 operating mechanism.

Each of the spreaders 52 is provided with 30 slideable members 60 and 61 guided for lateral movement by studs 62 and 63 passing through slots 64 and 65. The studs 63 may 35 be in the form of screws threaded into the sheet metal of the spreaders 52, while the studs 62 are preferably provided with a longer head through which the end of contractile springs may be inserted. The slideable members 60 and 61 are each provided 40 with studs 66 similar to the studs 62 and contractile springs 67 are arranged between each of the pairs of studs 62 and 66. These 45 springs act upon the slideable members 60 and 61 to move them to the extended position, as shown in dotted lines in Fig. 6 and in Fig. 7, the studs 62 and 63 guiding the slideable members. Suitable offsets 68 are provided in the slideable members 60 and 61 50 to permit them to pass one another when in collapsed position, as is clearly shown in Figs. 4 and 6.

Near the extreme edge of the slideable members 60 and 61 cords 69 are attached 55 and these cords are passed over pulleys 70 carried on lugs 57 and these cords are then carried down and fastened to a lug 71 on the standard 50.

In operating the machine of Figs. 4 to 7, 60 the operator takes a bag, such as shown in Fig. 8, and places it over the machine when it is in the position shown in Fig. 5. The operator then releases the latching mechanism and permits the spreading table to 65 drop down into extended position, such as

is shown in Fig. 7. During the downward movement of the spreaders 52, the pulleys 70 approach the lug 71 and, therefore, the cords 69 are loosened. The springs 67—67 urge the extensions 60 and 61 from the contracted position of Fig. 4 into the extended position of Fig. 7. During this operation, the bag is opened up and the bottom of it is stretched across the spreaders and the projecting end portions of the bag, which appear above the end of the spreaders 60 and 61 in the form of triangular flaps, are folded in toward the center of the table. The operator creases the bag around the outer edge of the spreading table, thereby 75 completing the forming of the formed bottom in the flat bag. The operator may then depress the treadle 16 to move the parts to the position of Figs. 4 and 5. The operator presses the bag, illustrated in dotted 80 lines in Fig. 7, inwardly at the points *t t* to initiate the infolded side tucks. The upward movement of the spreaders is accompanied by a retracting of the spreaders 60 and 61 so that the bag may be collapsed for 85 shipment, the position of the bag being indicated in dotted lines in Fig. 5. A finished bag is illustrated in Fig. 10, in which it will be noted that the parts *t t* have become the inner fold of the infolded side tucks and 90 that the excess projecting end portions have 95 been folded inside the collapsed bottom, as indicated at 72. The bag after being withdrawn from the machine is further collapsed to the position shown in Fig. 10 100 and is then ready for shipment. If it is desired to make a square bottom bag without infolded side tucks, the operator may 105 remove the bag from the machine in the manner discussed above with respect to the round bottom bag.

The periphery of the folding table is 110 preferably made approximately equal to twice the width of the flat bag B, which it is intended to use on the machine. In this way the bag is stretched out to its full extent without straining the paper and the bottom is formed in the bag that will fit the bottom of a barrel or box for which it is 115 designed. Bags or linings made in the manner described have been found to make very satisfactory linings for barrels and large boxes and it has been found that they can be made expeditiously on machines of the above type.

It is obvious that the machine as a whole and its different features, as herein shown and described, may be variously arranged without departing from the essentials of the invention. The present embodiment is therefore to be understood as illustrative 125 rather than restrictive, reference being had to the appended claims rather than to the foregoing description to indicate the scope of the invention.

The formed bottom bag or lining and 130

method of making the same constitutes the subject matter of another application for Letters Patent.

What is claimed is:

5. 1. A machine for forming bottoms in formless bottom bags, comprising a standard, spreaders carried by the standard and collapsible to receive the bag, and means to move the spreaders into a position to spread 10 the bag.
2. A machine for forming bottoms in formless bottom bags comprising spreading means having two positions in one of which it is folded edgewise to permit drawing 15 thereon the formless bottom bag, and in the other of which it spreads the bag, and means for moving the spreading means from one position to another.
3. A machine for forming bottoms in 20 formless bottom bags comprising a standard, spreaders disposed on opposite sides of the standard and adapted to occupy two positions, in one of which the spreaders are arranged parallel to each other to permit drawing thereon the formless bottom bag, and in the other of which they are arranged in the same plane to spread the bag and provide a folding surface, and means on said standard for moving the spreaders from one 25 position to another.
4. In combination, a standard, spreaders hinged opposite one another at the top of the standard and movable to provide a flat folding surface, means for simultaneously moving 30 the spreaders into said position, or to swing them toward one another about the hinges.
5. A machine for forming bottoms in formless bottom bags, comprising a standard, spreaders hinged to the top of the standard, a slidible member carried by the standard underneath the spreaders, members connecting the slidible member with the spreaders to move the same into either of 45 two positions, and a latch to hold the slidible member in the position in which the spreaders are extended.
6. A machine for forming bottoms in formless bottom bags, comprising a standard, 50 a member mounted to move along the standard, spreaders, and links intermediate the slidible member and the spreaders, said links operating to move the spreaders into collapsed or extended position upon movement of the slidible member.
7. A machine for forming bottoms in formless bottom bags, comprising a standard, a member mounted to move vertically 55 along the standard, spreaders, links intermediate the slidible member and the spreaders, said links operating to move the spreaders into collapsed or extended position upon movement of the slidible member, and means for moving the slidible member to extend 60 the spreaders.
8. A machine for forming bottoms in formless bottom bags, comprising a standard, a member mounted to move vertically along the standard, spreaders, links intermediate the slidible member and the spreaders, said links operating to move the spreaders into collapsed or extended position upon movement of a slidible member, and a treadle for moving the slidible member to extend the spreaders. 70
9. A machine for forming bottoms in formless bottom bags, comprising a standard, a member mounted to move vertically along the standard, spreaders, links intermediate the slidible member and the spreaders, said links operating to move the spreaders into collapsed or extended position upon the movement of a slidible member, and a latch to hold the slidible member in said 75 position.
10. A machine for forming bottoms in formless bottom bags, comprising a standard, a member mounted to move vertically along the standard, spreaders pivoted to the upper end of the standard, links intermediate the slidible member and the spreaders, said links operating to move the spreaders into collapsed or extended position upon movement of the slidible member, means for moving the slidible member to extend the spreaders, and a latch to hold the slidible member in said position. 80
11. A machine for forming bottoms in formless bottom bags, comprising a standard, a member mounted to move vertically along the standard, spreaders pivoted to the upper end of the standard, links intermediate the slidible member and the spreaders, said links operating to move the spreaders into collapsed or extended position upon the movement of the slidible member, a latch to hold the slidible member in said position, and a treadle for releasing the latch to permit the spreaders to be collapsed. 85
12. A machine for forming bottoms in formless bottom bags, comprising spreading means and means for operating the spreading means into either of two positions, in one of which positions a formless bottom bag may be placed over the spreading means, and in the other of said positions the bag is spread out to provide excess projecting end portions which may be folded against the spreading means to make 90 the formed bottom. 100
13. A machine for forming bottoms in formless bottom bags, comprising spreading means and means for operating the spreading means into either of two positions, in one of which positions a formless bottom bag may be placed over the spreading means, and in the other of said positions the bag is spread out to provide excess projecting end portions which may be folded 105
- 120
- 130

against the spreading means to make the formed bottom, the spreading means tending to assume the first position aforesaid.

14. A machine for forming bottoms in formless bottom bags, comprising spreading means, means for operating the spreading means into either of two positions, in one of which positions a formless bottom bag may be placed over the spreading means, and in the other of said positions the bag is spread out to provide excess projecting end portions which may be folded against the spreading means to make the formed bottom, and means for holding the spreading means in the last mentioned position.

15. A machine for forming bottoms in formless bottom bags, comprising spreading means, means for operating the spreading means into either of two positions, in one of which positions a formless bottom bag may be placed over the spreading means, and in the other of said positions the bag is spread out to provide excess projecting end portions which may be folded against the spreading means to make the formed bottom, the spreading means tending to assume the first position aforesaid, and means for holding the spreading means in the last mentioned position.

16. In combination, a standard, a member guided for vertical reciprocation along the standard, spreaders hinged to the standard, and connections between the spreaders and reciprocable member for operating the spreaders into extended or collapsed position.

17. Spreading means for flat bags without formed bottoms, comprising plates hingedly mounted along one edge, the periphery of said plates equaling approximately the periphery of the flat bags.

18. A machine for forming bottoms in formless bottom bags, comprising a standard, spreaders hinged to the top of the standard, means for upwardly swinging the spreaders, and means for retaining them in their upper position.

19. A machine for forming bottoms in formless bottom bags, comprising a standard, spreaders hinged to the top of the standard to have extended and collapsed positions, and a treadle for moving them to collapsed position.

20. In combination, a standard, spreaders hinged to the top of the standard, members slidably mounted on the spreaders, means for simultaneously moving the spreaders into a position to provide a flat folding surface and for moving the slidably mounted members to extend the folding surface.

21. In combination, a standard, spreaders hinged to the top of the standard, members slidably mounted on the spreaders, means for simultaneously moving the

spreaders into a position to provide a flat folding surface and for moving the slidably mounted members to extend the folding surface, said means including a member slidably carried on the standard and interconnected with both the spreaders and the slidably mounted members.

22. In combination; a standard; a member guided for vertical reciprocation along the standard; latching means for holding the member in elevated position; spreading devices mounted on the top of the standard and movable with collapsed or extended position, said spreading devices including movably mounted members; and interconnections between the reciprocable member and the spreading devices and movably mounted members for moving the devices and members into extended position when the reciprocable member is lowered.

23. A collapsible spreading table for forming bottoms in formless bottom bags, comprising, a central member and two spreaders hinged to the opposite sides of the central member, said spreaders being movable into a position to provide a flat table, and into a collapsed position.

24. A collapsible spreading table for forming bottoms in formless bottom bags, comprising, a central member and two spreaders hinged to the opposite sides of the central member, said spreaders being movable into a position to provide a flat table, and into a collapsed position, said spreaders including slidably mounted extensions for increasing the area of the table.

25. A collapsible spreading table for forming bottoms in formless bottom bags, comprising, a central member, two spreaders hinged to the opposite sides of the central member, said spreaders being movable into a position to provide a flat table, and into a collapsed position, said spreaders including slidably mounted extensions for increasing the area of the table, and devices for retracting the extensions when the table is collapsed.

26. A collapsible spreading table for forming bottoms in formless bottom bags, comprising, a central member, and two spreaders hinged to the opposite sides of the central member, said spreaders being movable into a position to provide a flat table and into a collapsed position, said spreaders including slidably mounted spring controlled extensions for increasing the area of the table.

27. A collapsible spreading table for forming bottoms in formless bottom bags, comprising, a central member, two spreaders hinged to the opposite sides of the central member, said spreaders being movable into a position to provide a flat table and into a collapsed position, said spreaders including slidably mounted spring controlled exten-

sions for increasing the area of the table, and devices for retracting the extensions when the table is collapsed.

28. A machine for making bags with formed bottoms out of flat bags without formed bottoms, comprising spreaders on which the bottoms may be formed, and means for collapsing the spreaders with the formed bottom of the bag between them 10 whereby the bag is collapsed for shipment.

29. A machine for making bags with formed bottoms out of flat bags without formed bottoms, comprising a horizontal bar, spreaders hinged to the sides of the bar 15 and movable upwardly toward one another to fold the formed bottom of the bag.

30. A machine for making bags with formed bottoms out of flat bags without formed bottoms, comprising a T-shaped 20 standard, a rod slidably mounted alongside the vertical part of the standard, means for raising the rod, a latch for holding the rod in raised position, and releasably to permit the lowering of the rod, spreaders hinged 25 to the horizontal part of the standard, and links interconnecting each spreader with the rod to move the spreaders upwardly about the hinges upon raising the rod, the spreaders dropping into extended position upon 30 releasing of the latch.

31. A machine for making bags with formed bottoms out of flat bags without formed bottoms, comprising a T-shaped

standard, a rod slidably mounted alongside the vertical part of the standard, means for 35 raising the rod, a latch for holding the rod in raised position, and releasable to permit the lowering of the rod, spreaders hinged to the horizontal part of the standard, and links interconnecting each spreader with the 40 rod to move the spreaders upwardly about the hinges upon raising the rod, the spreaders dropping into extended position upon releasing of the latch, each of the spreaders being provided with laterally slid- 45 able extensions, means retracting the extensions upon raising the spreaders, and spring means for moving the extensions outwardly when the spreaders are lowered.

32. A collapsible spreading table for 50 forming bottoms in formless bottom bags, comprising spreaders movable into a position to provide a flat table and into a collapsed position, said spreaders including 55 slidably mounted extensions for increasing the area of the table.

33. A collapsible spreading table for forming bottoms in formless bottom bags, comprising spreaders movable into a position to provide a flat table and into a collapsed position, said spreaders including 60 slidably mounted extensions for increasing the area of the table, and devices for retracting the extensions when the table is collapsed.

FRANCIS T. ROBINSON.
